UNITED STATES PATENT OFFICE.

ARNOLD KREUSLER, OF LOS ANGELES, CALIFORNIA.

SOUND-REPRODUCING INSTRUMENT.

1,318,675.

Specification of Letters Patent.

Patented Oct. 14, 1919.

Application filed January 18, 1919. Serial No. 271,854.

To all whom it may concern:

Be it known that I, ARNOLD KREUSLER, a citizen of the United States, residing at Los Angeles, in the county of Los Angeles, 5 State of California, have invented new and useful Improvements in Sound-Reproducing Instruments, of which the following is a specification:

This invention relates to sound reproducing instruments of the phonograph class; and the invention has particularly to do with the provision of a new kind of sound box and sound amplifying or resonating apparatus.

15 It is a peculiar feature of my invention that the needle which is actuated by the sound groove of a record is mounted directly upon, or is connected directly to, the sound amplifier or resonator in such a manner that 20 the vibrations of the needle are transmitted directly to the sound amplifier or resonator; rather than being transmitted to a diaphragm which then acts upon an air column which in turn transmits the vibration to a 25 resonator or amplifier, as is now usually the case. This peculiar feature of my invention may be embodied in many different ways; but in a certain desirable specific embodiment of my invention I may and do utilize 30 a violin as the sound amplifying or resonating element; and as a further feature of my invention in this specific embodiment of it, I make my arrangement such that, with a simple attachment to the violin and an extremely simple attachment to an ordinary 35 phonograph for the purposes of carrying the violin, I may enable any person having a phonograph to play a phonograph record with my improved apparatus. In its specific 40 violin-embodiment I find my invention peculiarly adapted to the reproduction of records made by stringed instruments; and, generally, I find that my apparatus reproduces very clearly and distinctly and without foreign vibrations all kinds of phonograph records; and I find a peculiar excellence in the reproduction of orchestral records, where my apparatus clearly reproduces the different instruments very distinctly.

45 My invention will be best understood from the following detailed description of a preferred embodiment of it, reference for this purpose being had to the accompanying drawings in which—

50 Figure 1 is an elevation showing the ap-

plication of my apparatus to a common form of phonograph; Fig. 2 is a sectional enlargement of a portion of Fig. 1; Fig. 3 is a section taken as indicated by line 3—3 on Fig. 2; Fig. 4 is a face view of my violin attachment taken as indicated by line 4—4 on Fig. 1; Fig. 5 is an enlarged detail section as indicated by line 5—5 on Fig. 2 and Fig. 6 is a detailed section taken as indicated by line 6—6 on Fig. 2.

55 In the drawings the numeral 10 designates the rotating record carrier of any ordinary phonograph and 11 designates the usual base board immediately below the record carrier; the numeral 12 designates the record on the record carrier. All the usual parts of such a phonograph are left unchanged by me; in fact, it is not necessary to remove the usual reproducing apparatus comprising the sound box and swinging sound arm, as my 60 apparatus may be applied to any phonograph without interfering with the usual sound box, etc. The only attachment which I make to the phonograph itself is a suitable support for the violin body. In actual practice this support may embody a member 12 which is bifurcated and has two prongs 12^a at its upper end, these two prongs being provided preferably with felt or other tips 65 as shown at 12^b; and the violin body 13 rests directly on these felt tips; the bifurcations 12^a straddling the strings 14 and the finger board 15. In this specific embodiment of my invention, it is an object to transmit the vibrations to the body of the violin through 70 both the finger board 15 and the bridge 16. In order to accomplish this, and also to do so with the simplest form of attachment, I provide an attachment which comprises a base 20 which is confined between the finger board 15 and the strings 14. This base 20 may be made of a suitable piece of wood 75 and may have felt pads 21 on its under side to bear against the fingerboard and other felt pads 22 over which the strings lie. The tension of the strings presses the base against the fingerboard and holds the base firmly in place. The strings need not necessarily be tuned; their function here is to press the base of my attachment against the finger board and, as in ordinary violin practice, to connect the fingerboard (at the point of contact with the strings, which in this case takes place through the base 20) with the bridge 16; so that to a certain extent all vibrations 80

which are transmitted to the fingerboard are also transmitted to the bridge 16 through the strings 14. But my attachment also transmits vibrations directly to the bridge 16. My attachment has a neck 21 preferably made of some resilient material. I find a thin strip of bamboo to be very useful for this purpose. This strip of bamboo may be glued to the forward end of base 20; and 10 the forward end of the neck 25 carries a head 26 which carries a socket 27 to hold the needle 28 at the correct angle to engage with the sound grooves of the phonograph record 12. The size and mass of this head 26 has 15 some bearing upon the efficacy of reproduction; and I find a head of about the size illustrated and made of hard wood to be very efficient. The socket 27 is set in the head and is made of metal. It has a needle 20 receiving bore 29 and this bore has a slot 30 in one side not quite wide enough to pass the needle. The screw 31 to hold the needle enters the socket from the side opposite the slot 30 and presses the needle against the two 25 edges of the slot; so that the needle has a three-point bearing and is thus held tightly and rigidly in place without any liability of displacement. Directly behind the head 26 I provide a bearing 32 on the neck 25, of 30 rather hard felt, which rests directly upon the bridge 16. When the device is put into position upon the violin the neck 25 is resiliently stressed so as to resiliently press the bearing 32 against the bridge. In the most 35 common type of phonograph and phonograph record to which my attachment is applicable, the vibrations in the record groove are transverse to the plane of the record and therefore the vibrations of needle 28 are horizontal. This kind of vibration sets up a vibration in the neck 25 which is characterized by being torsional and generally in a direction parallel to the face of the violin body rather than transverse of it. 40 Such vibrations are very similar to the vibrations of a violin string. The bearing 32 is rather narrow at its footing upon the bridge 16; so that the neck 25 is allowed to rock on the bearing 32; but in doing so it 45 of course transmits vibration to the bridge 16. The vibrations transmitted by the neck 25 are carried to the base 20 and are thence transmitted to the fingerboard 15. Or, considering the base 20 as being solidly mounted 50 upon the fingerboard 15, these vibrations are transmitted to the strings 14, and the strings 14 then transmit them to the bridge 16, and thence the vibrations are transmitted to the violin body. 55 The total operation of my attachment is 60 seen to be such that the vibrations are transmitted to the violin body or sound box in very much the same manner as they are transmitted from violin strings to the sound box when the violin strings are bowed in the

ordinary manner. As a consequence of all this, although I find my arrangement a peculiarly efficient one in the reproduction of all kinds of phonograph records, yet I find it to be most pleasingly efficient in reproducing the records of stringed instruments, and particularly of the violin itself. In fact, with my arrangement a record may be reproduced with the self same instrument from which it was originally made. 75 The part 26 is a small balance of regulator weight of felt, which I find improves the general reproduction qualities.

The violin body may be merely laid in place upon the supports 12^b, the weight of 80 the body holding it in place, and the point of support being near the neck of the violin so that there is a small unbalanced portion of the violin weight which holds the needle 28 in engagement with the phonograph 85 record grooves. In actual practice I do not find it necessary to utilize any means for positively holding the violin from displacement; but in some cases, to prevent the drag on the phonograph needle from dragging 90 the violin to the left in Fig. 2, a stop such as illustrated at 40 may be mounted upon the base 20 and engage with the support member 12 to prevent such motion. Stop 40 is merely a rod or pin set in member 22 and 95 projecting downwardly therefrom far enough to bear with its end against the stationary support 12. This stop leaves the violin free to turn in a horizontal plane, but keeps it from moving to the left, in Figs. 1 100 and 2. The mounting of the violin does not at all interfere with its movement which allows the needle 28 to follow the phonograph record; the violin gradually turning 105 in position as the needle moves inwardly toward the center of the record.

As a consequence of the simplicity and applicability of my invention, whenever a person desires to use it on a phonograph, it is only necessary to insert the needle properly 110 and then place the violin in position as illustrated. In placing the violin the stop 40 may be of use in putting it in about the right position, so as to put just about the right amount of weight on the phonograph 115 needle, and to get the needle in the proper relative position on the record. The record having been started in rotation, the needle is put into the beginning end of the groove, 120 and the reproduction ensues.

While I have described a specific embodiment of my invention with some particularity and detail, I do not thereby intend to limit my invention to this specific form of apparatus. Other specific forms of my invention will be readily apparent to those skilled in the art; and I do not delimit my invention from such other forms as it may take, except as is specifically stated in the following claims. 125 130

Having described a preferred form of my invention, I claim:

1. As a phonographic connection for a violin or like instrument, a needle holding member having a flat foot adapted to rest upon the fingerboard and to be confined between the fingerboard and the strings of the instrument by the tension of the strings. 35
2. As a phonographic attachment for a violin or like instrument, a needle holding member having a flat foot adapted to rest upon the fingerboard and be confined between the fingerboard and the strings of the instrument by the tension of the strings, 40 and having a bearing foot resting upon the bridge of the instrument.
3. As a phonographic attachment for a violin or like instrument, the combination of a flat base adapted to rest upon the fingerboard and be confined between the fingerboard and the strings of the instrument by the tension of the strings, a flexible neck connected with the base and having at its end a foot adapted to rest upon the bridge of the instrument, and having at said end a head adapted to carry a phonograph needle. 45
4. As a phonographic attachment for a violin or like instrument, the combination of a base adapted to be confined between the 50

fingerboard and the strings of the instrument, a flexible neck connected with the base and having at its end a foot adapted to rest upon the bridge of the instrument, and having at said end a head adapted to carry a phonograph needle, said neck being resiliently stressed when the device is placed in the described position upon the instrument so as to resiliently press the foot against the bridge. 55

5. As a phonographic attachment for a violin or like instrument, a needle holding member having at one end a flat base adapted to bear on the fingerboard of the instrument and having a bearing foot at the other end resting upon the bridge of the instrument. 60

6. As a phonographic attachment for a violin or like instrument, a needle holding member adapted to engage at one end with the strings near the instrument's fingerboard and having a bearing foot at the other end resting upon the bridge of the instrument. 65

In witness that I claim the foregoing I have hereunto subscribed my name this 13 day of January 1919.

ARNOLD KREUSLER.
